UNITED STATES PATENT OFFICE.

CHARLES MONSON, OF NEW HAVEN, CONNECTICUT.

AIR-COMPRESSOR.

SPECIFICATION forming part of Letters Patent No. 257,885, dated May 16, 1882.

Application filed March 26, 1881. (Model.)

To all whom it may concern:

Be it known that I, CHARLES MONSON, of the city and county of New Haven, in the State of Connecticut, have invented a new and useful Improvement in Air-Compressors; and I hereby declare the following to be a specification thereof, reference being had to the accompanying drawing, which is a central vertical section of my invention.

10 My invention relates to the general subject of air-compression; and it consists of one or more cylinders or air-pumps wherein the common atmosphere received from without through suitable valves is forced by a piston into the central chamber or reservoir of compressed air, and passes therein through valves of said chamber, which are alternately relieved from the resisting pressure of the compressed air by means of favorable currents produced at the entry-
20 ports by cylinders and pistons connected with said chamber, for the purpose as hereinafter more fully specified. The usual methods of compressing air are attended with this difficulty, that the pressure of the compressed air is continually increasing within the reservoir during the operation of pumping, until the pressure is so great as to effectually close the valves against the admission of any more air. Hence a continual increase of power is required
25 to move the pump, until at length no reasonable degree of power is able to force open the valves of the chamber against the accumulated pressure of the air confined therein. This difficulty is obviated by my invention. Whereas
30 in air-compressors as hitherto constructed the pressure is against the valves to resist the entrance of new accessions of air, I have discovered that this resistance may be overcome by causing currents of the compressed air itself
35 (or other fluid under pressure) to so move at and away from the entry-ports that the valves there placed are wholly relieved from the pressure of the compressed air within the chamber and readily open to the new air under pressure
40 of the piston of the air-pump.

45 In the drawing, A represents the central air chamber or reservoir for compressed air, (or other fluid or fluids under pressure.) Cylinders B B' are connected therewith on each side, opening into the chamber by the small ports a

a' at the top of the cylinders and the large ports b b' at the bottom.

In the cylinders B B' are the pistons C C', moving reciprocally and operated by power applied to a walking-beam. The cylinders B B' 55 and the chamber A contain compressed air only, (or other fluid under pressure.)

The cylinders D D' above the pistons are connected with the cylinders B B', respectively, and within them move reciprocally the pistons 60 E E', operated by power applied to said walking-beam. The cylinders D D' communicate at the top with the cylinders B B' by the small ports c c', and at the bottom they communicate with the chamber A by the long ports d d'. Flap- 65 valves e e' at the bottom of the cylinders D D' admit the outer air as the pistons E E' respectively rise.

A shuttle-valve, F, is supported and has a sliding movement within the standard G at the 70 bottom of the chamber A. It has at the ends the conical heads f f', which fit into seats of corresponding shape at the inner ends of the ports d d', as shown in the drawing. These cone-valves, if the cone is enlarged at its outer 75 or smaller end, will take increased force from the currents of both ports b d.

Having thus specified the construction of my improved air-compressor, I proceed to explain the method of its operation. Suppose 80 the chamber A to be filled with compressed air. This air will also fill the cylinders B B', both above and below the pistons C C', (except, as sometimes the case may be, water under pressure may occupy the spaces below the 85 pistons C C',) and the compressed air also fills the cylinders D D' above the pistons E E'. The chamber and cylinders have free and constant communication through the ports a a' b b' c c'. Now apply power to reciprocate 90 the pistons C C'. Suppose the piston C to be descending and the piston C' to be ascending. A current of compressed air (or other fluid) is driven downward in the cylinder B, out through the port b into the chamber A, and drawn in 95 through the port b', up under the piston C' of the cylinder B', and also from above the piston C' a current of compressed air is flowing out through the port a' into the chamber A, and through the port a into the cylinder B; 100

or, in other words, this movement of the pistons is causing the compressed air to flow from left to right at the bottom of the chamber and from right to left at the top of the chamber. 5 Now, simultaneous with this movement of the pistons C C' and the consequent currents of compressed air, as described, the pistons E E' are moving reciprocally, being operated by power, the former descending and the latter ascending in the cylinders D D', respectively. 10 The air, filling the lower part of the cylinder D under its piston, (being at the natural pressure,) descends as driven by the piston E, and, being prevented from escaping into the outer air by the closing of the flap-valve e, passes through the port d, and, impinging upon the end of the valve-head f, crowds it from its seat, and at the same time causes the valve-head f' to be seated at the opposite end of 15 the shuttle-valve F. This air rushes past the valve-head f and joins and mingles with the current of compressed air which is flowing at the same time, as above described, in the same direction through the port b into the chamber 20 A. The new air is thus imprisoned in the chamber A, and cannot escape, because as soon as the movements of the pistons E E' are reversed the valve-head f is again seated, and prevents egress, and the new air must mingle 25 with the volume of the compressed air, still further compressing it. As the piston E' ascends the flap-valve e' opens and the outer air rushes in to fill the lower part of the cylinder D' under the piston E'; but when the piston E' descends 30 the flap-valve e' closes and this new air is forced into the chamber A, in the same manner as above described. 35

In this manner the volume of the compressed air, which in all other compressors opposes 40 the entrance of new air, is compelled to move in currents facilitating such entrance, and the result is that I can obtain a higher degree of compression at the cost of less power, and, being provided with comparatively a moderate 45 amount of power, I need no increase of it. For example, it needs but little power to move down the piston E, for the common air which is driven downward by it has a powerful current of compressed air ready at the port d to escort 50 it into the chamber A. The twin piston E' will be prompt to rise, being sure of a place ready made for its discharge in chamber A, for as fast as the piston E descends it makes room in the chamber A for the piston E' to 55 discharge into. The pistons C C' E E' must yield to the power externally applied. Till then all are motionless. The still repose of pressure force is there; but it is a balanced pressure; but any movement of the pistons 60 unbalances that pressure, and the pressure in the direction of the movement of the pistons preponderates by precisely so much as the amount of the added power which has been externally applied. Because of the pressure of the 65 compressed air one-half is already in favor of the movement and one-half is opposed to the

movement. This results from the law of fluid-pressure, and is equally true whatever the degree of the pressure within may be. This is a novel and useful feature of my invention. I 70 balance the pressures of the compressed air between movable diaphragms or pistons of equal surface-pressure, which balanced pressures may be unbalanced at will in either direction by the application of external power 75 to a lever or walking-beam operating such diaphragms or pistons. As the pressure is uniform throughout the chamber A and on each side of the pistons in the cylinders B B', the pressure of the compressed air in favor of the 80 movement is exactly equal to the pressure opposing it, whatever the degree of the pressure may be, and a moderate outlay of external power can easily move the pistons, and the practical result is the creation of currents of 85 any desired velocity or force within the chamber and its ports, as above described.

Another novel and useful feature of my invention is the arrangement of the ports a a' c c', by which I am able to charge the descending pistons E or E' (as the case may be) with compressed air direct from the chamber A time after time, whatever the degree of the compression of said air may be, whereas in all other air-compressors the air-pump is working against 90 a continually and intensely accumulating pressure of the confined air. By my device that very pressure is made to assist the downward movement of the piston of the air-pump and to force the new installments of the external 95 air (that was) from beneath the piston E (or E') into the central reservoir.

It is obvious that this method is equally applicable to other fluids than air, or to other fluids with air, and useful results may be obtained by partially filling the chamber with water to produce strong currents at the ports b b' alternately to facilitate the entrance of the new air. It is also obvious that the principle which I claim may be embodied in other devices beside the one above specified—as, for example, I may use, instead of or as well as pistons to create the fluid movements, a rotating chamber, or rotation within a chamber, which may be partially filled with water, and 105 air and water currents may be formed therein (the water being under the air-pressure) by the centrifugal force generated in the denser fluid as the chamber (or other rotary) revolves; but any such variation of device would be within 110 my invention, an essential principle of which is the formation of fluid-currents in the reservoir of compressed air, into which currents the new air is taken and made to flow in the 115 same direction and to mingle its volume with that of the previously compressed air.

I therefore claim as a novel and useful invention and desire to secure by Letters Patent—

1. The cylinder B, discharging compressed 130 air through its port b into the air-chamber A by means of the piston C, in combination with

the cylinder D, discharging natural air through its port *d* into the air-chamber A by means of its piston E, said pistons descending simultaneously within their respective cylinders for 5 the purpose of injecting a current of natural air into a current of compressed air while both currents are moving in the same direction, substantially as specified.

2. The combination of the air-chamber A, 10 the cylinders B D, the pistons C E, the ports *a b c d*, and valve *e*, to facilitate the descent of the piston E in its cylinder D by the pressure

of the compressed air upon its upper surface, substantially as described.

3. The improved air-compressor herein de- 15 scribed, consisting of the chamber A, cylinders B B' D D', pistons C C' E E', ports *a a' b b' c c' d d'*, valves *e e' F*, and standard G, all operating substantially as shown, and for the purpose specified.

CHARLES MONSON.
